ROCKER

Louis A. Haug, Dubuque, Iowa

Application March 12, 1934, Serial No. 715,213

3 Claims. (Cl. 155—71)

This invention relates to rockers especially adapted for children to afford amusement with a maximum amount of safety and comfort, and has for the primary object the provision of a device which will be durable and cheap to manufacture and will be easy to operate so that comparatively young or small children may successfully use the device.

With these and other objects in view this invention consists in certain novel features of construction combination and arrangement of parts to be hereinafter more fully described and claimed.

For a complete understanding of my invention, reference is to be had to the following description and accompanying drawing, in which

Figure 1 is a top plan view, partly in section, illustrating a rocker constructed in accordance with my invention.

Figure 2 is a vertical sectional view illustrating the same.

Figure 3 is a fragmentary sectional view taken on the line 3—3 of Figure 2.

Figure 4 is a fragmentary transverse sectional view taken on the line 4—4 of Figure 2.

Figure 5 is a fragmentary sectional view showing the connection between the spring means and the rocker structure.

Referring in detail to the drawing, the numeral 1 indicates an elongated frame, the side members of which form tracks 2 on which rocker elements 3 operate. The rocker elements 3 are provided with arcuately curved faces 4 so that said rocker elements on the tracks 2 may rock backward and forward. The rocker elements are joined by a seat structure 5 consisting of a seat 6, back 7 and feet and toe boards 8 and 9, respectively. The rocker elements slightly in advance of the seat 6 are cut away to form side entrances 10 to permit a child to readily enter and exit from the device. Supporting members 11 are secured to the rocker elements in advance of the entrances 10 and extend from the floor board 8 upwardly beyond the upper edges of the rocker elements and in advance of the seat 6 and are connected by a hand rail 12 which is positioned to be easily grasped by a child when sitting upon the seat 6.

A substantially U-shaped frame 13 is positioned horizontally and is secured to the tracks 2 with the bight portion of said frame traversing the space between the tracks and has adjustably connected thereto an anchoring element 14 to which one end of a coil spring 15 is secured. The other end of the spring 15 is connected to a plate 16

and the latter is pivoted to a hanger 17. The hanger is provided with a bifurcated portion between which is pivoted the plate 16 and one end of a connecting link 18. A shaft 19 is connected to the tracks and extends through the arm portions of the frame 13 and has journaled thereon the hanger 17. A U-shaped support 20 is journaled on the shaft 19 with its arm portions 21 extending upwardly and carrying a shaft 22 on which is journaled the upper end of the link 18. The arm portions 21 of the frame 20 are capable of a rocking motion on the shaft 19 by the rocking movements of the rocker elements 3. The shaft 22 is connected to a sub-frame 23 mounted to the seat structure 5, as shown in Figure 4, by connecting members 24 each of which consists of a substantially triangular-shaped element as suggested in Figure 4. The connecting members 24 are journaled to the shaft 22 and pivoted to the subframe 23. This triangular-shaped element provides strength to each of the members 24 and prevents shifting of the connecting member or link 18 on the shaft 22.

The normal position of the rocker elements is as shown in Figure 2 with the spring 15 under a slight tension. A child occupying the seat 6 leans first forwardly and then backwardly to start the rocking motion of the rocking elements on the track and this rocking motion is aided by the spring 15. It is to be understood that the spring 15 receives its greatest tensioning when the rocker elements reach approximately the limit of their rocking motion in either direction so that when the child shifts its weight the spring acts to aid in moving the rocking elements in a reverse direction. The arrangement of the spring and its connection with the rocking elements also prevents the latter from rocking in either direction to an extent that it would be dangerous to the child occupying the seat.

The rocking motion of the rockers on the track cause a forward and rearward swinging movement of the shaft 22 due to the latter being connected to the subframe 23 by the connecting members 24. The shaft 22 being connected to the hanger 17 by the link 18 will cause said hanger to swing upwardly and downwardly on the shaft 19 during said swinging movement of the shaft 22.

The upward and downward movement of the hanger 17 increases the tension of the spring 15. Thus it will be seen that the spring acts to aid the rocking movements of the rockers on the track.

Having described the invention, I claim:

1. A rocker comprising a rocker structure, a support for supporting said rocker structure, a pivotal frame pivoted to the support, spring means connected to the support, a member pivoted to the support and pivotally connected to said spring means, means connecting the rocker structure to the pivotal frame, and means connecting the pivotal frame to said member.
5
- 10 2. A rocker comprising a rocker structure, a support for supporting said rocker structure, a shaft secured to the support, a movable frame journaled to the shaft, connecting elements journaled to the movable frame and pivoted to the rocker structure, a spring adjustably connected to the support, a platelike member journaled to the shaft and pivotally connected to the spring, and a link pivotally connected to the movable frame and to the plate-like member.
15

the shaft and pivotally connected to the spring, and means connecting said member to the movable frame.

3. A rocker comprising a rocker structure, a support for supporting said rocker structure, a shaft secured to the support, a movable frame journaled to the shaft, connecting elements journaled to the movable frame and pivoted to the rocker structure, a spring adjustably connected to the support, a platelike member journaled to the shaft and pivotally connected to the spring, and a link pivotally connected to the movable frame and to the plate-like member.
